UNITED STATES PATENT OFFICE.

EDWARD F. GRANDY, OF SWAMPSCOTT, MASSACHUSETTS, ASSIGNEE TO UNITED SHOE MACHINERY CORPORATION, OF PATERSON, NEW JERSEY, A CORPORATION OF NEW JERSEY.

TREADLE-CONTROL MECHANISM.

1,290,175.

Specification of Letters Patent.

Patented Jan. 7, 1919.

Application filed April 1, 1918. Serial No. 225,975.

To all whom it may concern:

Be it known that I, EDWARD F. GRANDY, a citizen of the United States, residing at Swampscott, in the county of Essex and State of Massachusetts, have invented certain new and useful Improvements in Treadle-Control Mechanisms; and I do hereby declare the following to be a full, clear, and exact description of the invention, 10 such as will enable others skilled in the art to which it appertains to make and use the same.

The present invention relates to treadle control mechanisms and more particularly 15 to mechanisms of this character employed in connection with machines which automatically complete a predetermined cycle of operations upon an initial depression of the treadle.

It sometimes happens in connection with 20 machines of this type that unauthorized persons in passing the machine depress the treadle and start the machine. This momentary depression of the treadle may work serious injury in machines of the type referred to, as the machine after once being 25 started completes the predetermined cycle of operations whether or not the pressure upon the treadle is continued or relieved.

It is the object of the present invention to 30 provide a simple and compact mechanism for preventing the operation of the treadle by unauthorized persons and to this end a feature of the present invention contemplates 35 the provision of a locking pin slidably received in a stationary support located at one side of the treadle arm and a pivoted lever connected to the pin and adapted upon actuation to project the end of the pin beneath the treadle arm and retain the treadle in an elevated position.

This mechanism is particularly intended 40 for use in connection with sole molding machines of the type disclosed in the patent to Preble, No. 1,004,076, Sept. 26, 1911, and as constructed is capable of embodiment in these machines without any change or modification of the machines themselves.

Still further features of the invention 50 consist in certain novel features of construction, combinations and arrangements of parts hereinafter described and claimed, the advantages of which will be obvious to those skilled in the art from the following description.

In the accompanying drawings illustrating the preferred embodiment of the invention, Figure 1 represents a side elevation of the treadle locking mechanism, together with the treadle and connected parts; and Fig. 2 60 is a front elevation of the mechanism shown in Fig. 1.

In the construction shown in the drawings a treadle arm 10 is fulcrumed at its rear end upon a rod 12 forming a part of the 65 machine frame 13. This treadle arm is connected with a rock shaft 14 through an adjustable link 16 and an arm 17 projecting from the rock shaft, as shown clearly in the drawings. The rear end of the rock shaft 70 14 carries a second and vertically disposed arm 18 connected at its upper end with a collar 20 splined upon a drive shaft 21. The collar 20 carries a roll 22 which is engaged by one end of a lever 23 pivoted 75 on a hub 24 and having a cam 25 formed upon the opposite end which engages between the ends of a clutch band 26 to expand the band against a drive pulley 27, thus locking the pulley to the shaft 21. When 80 the roll 22 is moved from under the end of the lever 23 the cam shaped end is moved into an inoperative position by a spring 28. The clutch band is connected to the hub 24 by a block 29 bolted to the band and received in a slot formed in the hub. Immediately upon starting the drive shaft an arm 30 is moved into engagement with a lug 31 85 projecting upwardly from the treadle arm to hold the treadle in a depressed position until the machine has completed its cycle of operations, when the arm is removed to permit elevation of the treadle by a spring 32.

It will be obvious that with this construction a momentary depression of the treadle will serve to start the mechanism into operation and that thereafter this operation will be continued independently or whether or not the treadle is subsequently released. 90 It is possible, then, for the machine to be seriously injured if an unauthorized person in passing the machine carelessly steps on the treadle and to prevent this occurrence means are provided for locking the treadle in elevated position when it is not desired that the machine should be used. This mechanism is conveniently adapted to existing types of machines and to this end a stationary support or arm 35 is provided 105 110

with a split hub, indicated at 36, which is adapted to be clamped over a brace rod 37 connecting opposite sides of the frame in this machine. This support is located at 5 one side of the treadle arm and slidingly receives a pin 38 which is adapted at one end to project beneath the treadle arm 10. The opposite end of the locking pin 38 is connected to an actuating lever 40 pivoted centrally upon a lug 42 projecting from the support 35 and having a forked lower end which embraces a stud 43 secured in the locking pin 38. With this construction a simple manipulation of the upper end of the 10 actuating lever, which is conveniently accessible to the foot of the operator, moves the end of the locking pin either into or out of the path of movement of the treadle arm, as desired. The operative or inoperative 15 positions of the locking pin are determined by a spring pressed detent 45 located in the support 35 and engaging with one of a pair of recesses 46 formed in the pin 38. This mechanism forms a simple and compact construction which in its normal position does not interfere with the free operation of the 20 treadle but which may be actuated when so desired to positively prevent any depression of the treadle when the machine is not 25 in use.

While it is preferred to employ the specific construction and arrangement of parts shown and described, it will be understood 30 that this construction and arrangement is not essential except so far as specified in the 35 claims, and may be changed or modified without departing from the broader features of the invention.

The invention having been described, what is claimed is:

1. A treadle control mechanism comprising a pivoted treadle arm, a support located at one side of the path of movement of the arm, a locking pin slidingly received in the support and adapted in one position to project beneath the treadle arm when elevated and in another position to be removed from the path of movement, and an actuating lever pivoted upon the support and connected to the opposite end of the pin to move the pin into and out of the path of movement of the treadle arm. 40

2. A treadle control mechanism comprising a pivoted treadle arm, a transverse brace rod, a stationary supporting arm having a split hub clamped upon the rod, a locking pin received in the supporting arm and normally located at one side of the path of movement of the treadle arm, and an actuating lever pivoted upon the supporting arm 45 and connected at one end to the pin to project the opposite end of the pin beneath the treadle arm when in elevated position. 50

3. A treadle control mechanism comprising a pivoted treadle arm, a driving clutch, connections between the treadle arm and clutch for engaging the clutch when the arm is depressed, means for locking the treadle arm in depressed position after the clutch is engaged, a locking pin supported at one side of the treadle arm in a normally inoperative position, and means for projecting the end of the locking pin beneath the treadle arm to lock the latter in elevated position and prevent starting of the machine. 55

EDWARD F. GRANDY.
